Nelson W. Howard

UNITED STATES PATENT OFFICE

THOMAS PERCY HALL, OF LEICESTER, ENGLAND, ASSIGNOR TO UNITED SHOE MACHINERY CORPORATION, OF PATERSON, NEW JERSEY, A CORPORATION OF NEW JERSEY

MACHINE FOR APPLYING STRIPS OF PIPING TO SHEET MATERIAL

Application filed April 15, 1930, Serial No. 444,593, and in Great Britain May 15, 1929.

This invention relates to machines for applying to a piece of sheet material a strip of sheet material to provide an ornamental edge and is herein illustrated as embodied in a machine for applying to a leather shoe part an adherent strip of piping in such manner that the edge of the piping extends beyond the edge of the leather.

In the manufacture of shoes it is customary in some instances to prepare a strip of piping, commonly made of leather, and usually of a colour different to the main parts of the shoe upper and to apply this strip of piping to a margin of a vamp, quarter or other part of a shoe upper in such manner that one edge of the piping extends beyond the edge of the shoe part so as to be exposed in the finished shoe as an ornament.

To this end there is provided, in accordance with one feature of the invention, a support over which a piece of sheet material is fed, a guide for engaging the edge of the material, means for directing a strip of piping upon the material with its edge projecting beyond the edge of the material, and means for pressing the piping against the material. In the illustrated machine the piping is directed upon the sheet material at a locality alongside the edge guide considered in the direction of feed movement of the work, and a cooperating hammer and anvil act to press the piping against the material and to feed the piping and the material, it being understood that either the strip of piping or the margin of the sheet material or both have been previously coated with an adhesive.

It is desirable to provide for controlling the extent to which the piping extends beyond the edge of the material and to this end in accordance with another feature of the invention provision is made for relatively adjusting the strip or piping guide and the guide for the edge of the material. In the illustrated machine the strip guide is spring pressed toward the work, and is mounted in a carrier which is pivoted about an axis extending parallel to the direction of feed movement of the work, so that, when the strip guide is adjusted angularly about its pivot, it remains in contact with the work

and moves transversely of the edge thereof to cause the piping to extend more or less beyond the edge of the material.

These and other features of the invention including certain details of construction and combinations of parts will be described as embodied in an illustrative machine and pointed out in the appended claims.

Referring now to the accompanying drawings,

Fig. 1 is a front elevation of a portion of a machine in which the present invention is embodied;

Fig. 2 is a rear elevation of the same portion of the machine; and

Fig. 3 is an end elevation of part of the same portion of the machine.

The margin of the piece of sheet material, such as a leather shoe part, is fed away from the observer as viewed in Fig. 1, over a support comprising the top of a block 5 and the top of a plate 7 with its edge in contact with an edge guide 9, there being a lever 11 the lower edge of which is located in a groove in the edge guide 9 and extends over the margin of the sheet material to prevent it from rising. On the farther side of the lever 11 is a strip guide 13 of the shape shown having a substantially horizontal lower portion in the under side of which is a channel 15 (Fig. 2) through which the piping strip passes. This strip guide 13, is located above and normally rests upon the top surface of the material edge guide 9, but may be raised off the material edge guide during the operation of the machine depending upon the thickness of the material. A piece of sheet material 100 and a strip of piping 200 are shown in Fig. 3 in process of going through the machine, the strip of piping being led to the strip guide 13 through a substantially upright lead tube 17 attached to a lever 19 which carries the strip guide. On the farther side of the strip guide, as viewed in Fig. 1, is a presser and feed member in the form of a hammer 21 and an anvil 23, best shown in Fig. 2, which act, as will presently be described, both to press the piping against the material and to feed both the piping and the material.

The machine has a frame very much like

that of the folding machine shown in Letters Patent No. 1,702,598, granted February 19, 1929, upon an application filed in the name of Perley R. Glass, said frame comprising a lower arm 25, which carries the edge guide 9, the hammer 21 and the anvil 23, and an upper arm 27 which carries the other work-engaging parts. The stem of the hammer is pivoted to the stem of the anvil at 29, and this stem at its lower end is fast to a horizontal sleeve 31 mounted for rocking movement in a bearing in the lower arm 25. The lower end of the stem of the hammer is pivoted at 33 to a rod 35 which extends through the sleeve 31. In the operation of the machine, the rod 35 is pulled to the left (as viewed in Fig. 2) to bring the hammer down upon the work. The sleeve 31 is then rocked in a direction to cause the hammer and anvil to swing toward the observer to feed the work. At the end of the feed movement, the rod 35 is moved to the right to cause the hammer to free the work, and then the sleeve 31 is rocked to return the hammer and anvil to the positions shown. Any suitable mechanism may be employed to actuate the rod 35 and the sleeve 31 in the manner which has been described, for example that shown in the patented machine. During the backward movement of the hammer and anvil, that is during their movement in a direction away from the observer as viewed in Fig. 2, the anvil 23 is in contact with the under face of the work and tends slightly to drag it backward. One purpose of the block 5, which has been referred to above, is to counteract this tendency. This block is mounted at the outer end of a small rock-shaft 37 carried by the lower arm, said shaft being rocked at the proper time to cause the block 5 to press the work up against the under side of the strip guide 13 and hold it firmly while the hammer and anvil are moving backward along the work. This block and shaft, together with its operating mechanism (not shown) are or may be substantially like the corresponding parts shown in the patented machine.

The stem of the strip guide 13 (Fig. 3) is 50 slidable vertically in a vertical bore in the outer end of the lever 19, said bore having an enlarged upper portion to receive a spring 37 which rests at its lower end upon the head of the stem, and at its upper end engages the bottom of a screw 39 threaded into the top of 55 the enlarged portion of the bore. This lever 19 is pivoted at 41 between two small brackets 43, 45 carried by the upper arm 27 and has at its inner end a finger piece 191. The lever 19 (see Fig. 2) has pivoted to it at 47 a small 60 upwardly extending rod 49 the upper end of which is threaded into a bore in the depending portion of a cap 51; said depending portion being slidable in a bore formed in a part rigid with the arm 27. A coiled spring 53 acts to push up the cap 51 and, through the

small rod 49, to pull up the rear end of the lever 19 (the left-hand end as viewed in Fig. 2). A stop screw 55, which is threaded through the lever and abuts a stationary part limits the upward movement. With this construction, when the lever 19 is adjusted angularly about its pivot 41, the strip guide 13, due to the fact that it is held down by the spring 37, will be adjusted transversely of the edge of the material so as to vary the extent to which the strip of piping projects beyond the edge of the material. 70

The lever 11 is pivoted at 57 to a bell-crank lever 59, said bell-crank lever being in turn pivoted at 61 to a small stationary bracket 63. A tension spring 65 connects the upper end of the bell-crank lever 59 to a finger-piece 111 on the lever 11; said finger-piece being engaged by an adjusting screw 67. An adjusting screw 69, threaded through the upper part of the bell-crank lever 59 abuts against the bracket 43; and these two screws furnish means for adjusting the lever 11 to bring its operative portion into proper position. 80

Before being operated upon by the machine 90 it will be understood that the piping strip or the margin of the shoe part or both have been coated with cement. The free end of a suitably mounted spool of piping is led through the tube 17, through the channel 15 in the piping guide 13 and into the field of action of the hammer and anvil. The piping guide is lifted by depressing the finger piece 191 and the material, for example a shoe part, placed, display side down, with its edge 95 against the edge guide 9. The piping guide is then released, and the machine started whereby the piping will be applied to the shoe part in the desired manner. At the 100 end of the operation the piping is severed 105 leaving a portion of the piping between the hammer and the anvil.

Although the invention has been set forth as embodied in a particular machine, it should be understood that the invention is not limited in the scope of its application to the particular machine which has been shown and described. 110

Having thus described the invention, what I claim as new and desire to secure by Letters Patent of the United States is: 115

1. A machine of the class described having, in combination, a support over which a piece of sheet material is fed, a guide for engaging the edge of the material, means for directing a strip of piping upon the material, with its edge projecting beyond the edge of the material, and means for pressing the piping against the material. 120

2. A machine of the class described having, in combination, a support over which a piece of sheet material is fed, a guide for engaging the edge of the material, means for directing a strip of piping upon the material with its edge projecting beyond the edge of the material, and means for pressing the piping 125 130 135

against the material, said directing means and guide being relatively adjustable to vary the extent to which the edge of the piping projects beyond the edge of the material.

5 3. A machine of the class described having, in combination, a support over which a piece of sheet material is fed, a guide for engaging the edge of the material, means for directing a strip of piping upon the material with its 70
10 edge projecting beyond the edge of the material, and means for pressing the piping against the material, said directing means being adjustable to vary the extent to which the edge of the piping projects beyond the edge 75
15 of the material.

4. A machine of the class described having, in combination, a support over which a piece of sheet material is fed, guiding means for engaging the edge and a marginal portion 80
20 of the upper face of the material, a guide for a strip of piping located to direct the piping upon the material at a locality alongside said guiding means considered in the direction of feed movement of the material with the edge 85
25 of the piping projecting beyond the edge of the material, and means for pressing the piping against the material.

5. A machine of the class described having, in combination, a support over which a piece 90
30 of sheet material is fed, guiding means for engaging the edge and a marginal portion of the upper face of the material, a guide for a strip of piping located to direct the piping upon the material at a locality alongside said 95
35 guiding means considered in the direction of feed movement of the material with the edge of the piping projecting beyond the edge of the material, and means for pressing the piping against the material, said piping guide 100
40 being adjustable to vary the extent to which the piping extends beyond the edge of the material.

6. A machine of the class described having, in combination, a support over which a piece 105
45 of sheet material is fed, a guide for engaging the edge of the material, a guide for a strip of piping located above said material guide in position to direct the piping to the material with the edge of the piping projecting beyond 110
50 the edge of the material and means for pressing the piping against the material.

7. A machine of the class described having, in combination, a support over which a piece of sheet material is fed, a guide for engaging 115
55 the edge of the material, a guide for a strip of piping located above said material guide in position to direct the piping to the material with the edge of the piping projecting beyond the edge of the material, and 120
60 means for pressing the piping against the material, said piping guide being adjustable transversely of the edge of the material to vary the extent to which the piping projects beyond the edge of the material.

8. A machine of the class described hav- 125
65

ing, in combination, a support over which a piece of sheet material is fed, a guide for engaging the edge of the material, a pivoted guide for directing the piping upon the material with its edge projecting beyond the 70
75 edge of the material, said guide being adjustable about its pivot to vary the extent to which the piping projects beyond the edge of the material, and means for pressing the piping against the material.

9. A machine of the class described having, in combination, a support over which a piece of sheet material is fed, a guide for engaging the edge of the material, means for directing a strip of piping upon the upper face of the 80
85 material with its edge projecting beyond the edge of the material, and a cooperating hammer and anvil for pressing the piping against the material and for feeding the piping and the material.

10. A machine of the class described having, in combination, a support over which a piece of sheet material is fed, a guide for engaging the edge of the material, a guide for directing a strip of piping upon the material 90
95 with its edge projecting beyond the edge of the material, a carrier for said strip guide, a pivot about which the carrier may be adjusted, means for mounting the guide for yielding movement toward and from the material whereby adjustment of the carrier about its pivot moves the operative portion of the guide substantially transversely of the edge of the material, and means for pressing the piping against the material. 100

In testimony whereof I have signed my name to this specification.

THOMAS PERCY HALL.
